ATTORNEYS

UNITED STATES PATENT OFFICE.

JOHN M. GROFF, OF CANTON, OHIO.

COMBINED CHAIR AND LOUNGE.

SPECIFICATION forming part of Letters Patent No. 416,837, dated December 10, 1889.

Application filed June 17, 1889. Serial No. 314,609. (No model.)

To all whom it may concern:

Be it known that I, JOHN M. GROFF, a citizen of the United States, residing at Canton, in the county of Stark and State of Ohio, have invented certain new and useful Improvements in Combined Chair and Lounge; and I do hereby declare that the following is a full, clear, and exact description of the same, reference being had to the annexed drawings, making a part of this specification, and to the letters of reference marked thereon, in which—

Figure 1 is a view showing the position assumed by the different parts when the same is folded to form a chair. Fig. 2 is a detached view of the retaining-racks and handle. Fig. 3 is a view showing the position of the different parts when the same are folded to form a lounge. Fig. 4 is a detached top view 20 of one of the connecting-joints. Fig. 5 is a side view of one of the connecting-joints, showing a part of the veneering broken away.

The present invention has relation to combined chair and lounge; and it consists in the 25 different parts and combination of parts hereinafter described, and particularly pointed out in the claim.

Similar letters of reference indicate corresponding parts in all of the figures of the 30 drawings.

In the accompanying drawings, A B represent the base, which consists of bars properly attached together, as illustrated in the drawings. The back C is pivotally attached 35 to the upper end of the base-piece A. The side rails or bars a of the back C extend some distance below the top of the base-piece A, and are connected at their lower ends by the cross-bar B'. The bolts c, which connect 40 the side rails or bars a with the base A B, are formed long enough to receive and hold the seat-rails d, said seat-rails being connected at their opposite ends to the cross-bolt D, which cross-bolt connects the head-rails E and the 45 arms F to the top or upper ends of the base-pieces B.

To the cross-bolt D are pivotally attached the retaining-racks H. When it is desired to form a chair, the back C is elevated to the 50 desired inclination and the bar B' is engaged with one of the notches in the retaining-rack,

thereby securely holding the back C, together with its different parts, in the desired position, at which time the head-rails E, together with their slats, are free to assume the position illustrated in Fig. 1. These head-rails are bent or curved for the purpose of providing a suitable form for the head end of the lounge when the back C is placed in a horizontal position, as illustrated in Fig. 3. For 55 the purpose of securely holding the head-rails E in the position shown in Fig. 3, together with their slats g, the curved extensions h are provided for the purpose of engaging the ends of the side rails or bars a, and thereby 60 hold the head end of the lounge in the proper elevated position.

For the purpose of setting the back C at any desired angle to the seat F', a series of notches d' are provided in the retaining racks 70 or bars H. To the free ends of the arms F are pivotally attached the arms G, the opposite ends of these arms being pivotally attached to the side rails or bars a, and are for the purpose of providing resting-arms for the 75 chair proper.

For the purpose of providing neat joints, the heads and nuts of the clamping-bolts are countersunk, as illustrated in Figs. 4 and 5, and said heads and nuts covered by suitable 80 veneering.

It will be understood that the weight of a person will hold the head-rails E in the position illustrated in Fig. 3, and the back proper will be prevented from tilting by the end of 85 the side rails a coming under the curved portion h.

The side rails a and the head-rails E are placed in the same plane, whereby it is possible that said parts may engage when 90 brought into the reclining position shown in Fig. 3.

It will be understood that the back, seat, and head may be upholstered, if desired.

Having fully described my invention, what I 95 claim as new, and desire to secure by Letters Patent, is—

The combination of the base A B, the side bars or rails a, pivotally attached to the base-pieces A, the seat F', the head-rails E, provided with the curved extensions h and located in the same plane with the side rails a 100

and adapted to engage the lower ends of the side rails *a*, said head-rails being pivotally attached to the base, the retaining-bar *H*, provided with a series of notches *d'*, adapted 5 to be engaged with the bar *B'*, all arranged substantially as and for the purpose set forth.

In testimony that I claim the above I have

hereunto subscribed my name in the presence of two witnesses.

JOHN M. GROFF.
